UNITED STATES PATENT OFFICE.

JOHN H. J. HAINES, OF NEW YORK, N. Y., ASSIGNOR TO WILLIAM A. SWEETSER AND HENRY S. ELLIOTT, OF NEW YORK, N. Y.

ICE-MAKING MACHINE OR APPARATUS.

SPECIFICATION forming part of Letters Patent No. 729,929, dated June 2, 1903.

Application filed January 19, 1903. Serial No. 139,662. (No model.)

To all whom it may concern:

Be it known that I, JOHN H. J. HAINES, a resident of New York, State of New York, have invented a new and useful Improvement in Ice-Making Machines or Apparatus, which invention is fully set forth in the following specification.

My invention relates to ice-machines of that class in which the rapid expansion of a gas (preferably reduced to a liquefied state by compression) is employed to reduce the temperature of the liquid to be frozen to or below the freezing-point.

The object of the invention is to provide a machine or apparatus of the class referred to which shall operate efficiently on a commercial scale with a gas that may be obtained at a low initial cost and which is capable of compression to the desired degree with the expenditure of a minimum amount of power, thereby rendering possible the production of ice on a large scale at a very low cost.

With this object in view the invention consists in a gas-expansion chamber inclosing a refrigerating-chamber and having its top in communication with a reservoir containing a compressed gas, preferably liquefied, and also in communication from a point at or near its top with a pump which acts to exhaust the gas from the gas-expansion chamber and recompress it and deliver it to a suitable reservoir, which for convenience may be the reservoir from which it passed to the expansion-chamber. The gas I prefer to employ is sulfurous dioxid, (SO_2), which has a very low critical point, and hence is capable of compression to liquefaction with the expenditure of a small amount of power; but I have found that when a reservoir of this liquefied gas is placed in communication with the gas-expansion chamber surrounding the refrigerating-chamber a considerable amount of the gas passes over into the expansion-chamber in a liquid state, so that before the machine has been operated for any considerable length of time the liquefied gas gradually fills the expansion-chamber or greatly reduces the volume thereof, thereby decreasing the efficiency of the machine or apparatus and eventually clogging it to such an extent that it cannot be operated economically, if at all.

To obviate this difficulty, I have devised an automatic valve mechanism interposed between the reservoir and the expansion-chamber, which valve mechanism operates to 55 nearly if not entirely prevent the passage of the liquid gas, while permitting the free passage of the necessary amount in a gaseous form.

I have illustrated in the accompanying dia- 60 grammatic drawings one mechanical expression of the inventive idea; but it is to be understood that such drawings are illustrative only and are not designed to define the limits of the invention, this being done by the 65 claims herein.

In said drawings, Figure 1 is a diagrammatic view of the apparatus, and Fig. 2 is a detailed sectional view of the automatic valve mechanism.

Referring to the drawings, 1 is a box made of any suitable material, and 2 is a smaller box, so placed within box 1 as to leave a considerable space between the sides and bottoms of the two boxes, which space is hermetically 75 sealed around the top edges of the boxes. This intervening space constitutes the gas-expansion chamber of the apparatus. A compressed-gas reservoir 3 has a pipe or conduit 4, leading from a point near the bottom of 80 the reservoir 3 to the expansion-chamber, which it enters at or near its top. A second pipe or conduit 5 leads from the top of the expansion-chamber to the suction side of a vacuum-pump or compressor 6, while a pipe 85 7 leads from the compression side of the pump to the reservoir 3, preferably passing through a condenser or cooling-tank 8, through which a current of cold water is directed by means of pipes 9 and 10. Preferably the cold water 90 enters at the bottom pipe 9 and flows out through the top pipe 10, because the warmer water will naturally rise to the top, and the body of water in the cooler or condenser will thus be kept cooler than it would be if the current were reversed. The gas which I prefer to employ is sulfurous dioxid, (SO_2), because it can be purchased on the market at a very low price and because its critical point is very low, and it can therefore be compressed to 100 liquefaction by a single-action compression-pump, which can be operated by a minimum

amount of power, whereas if a gas having a high critical point were employed it would necessitate the use of a double-action pump, with a corresponding increase in the power required to operate it.

One of the difficulties incident to the use of a gas with a low critical point, like sulfurous dioxid, lies in the fact that the gas does not pass as rapidly from the liquid to the gaseous state at a given temperature and pressure as a gas having a higher critical point, and hence the gas is liable to pass into the expansion-chamber in considerable quantities in the form of a liquid, thereby clogging the apparatus and interfering with its efficiency. In order to obviate this difficulty, I introduce an automatic valve device 11 into the pipe 4 between the liquid-gas reservoir 3 and the gas-expansion chamber 4, and preferably at or near the point where the pipe 4 enters the expansion-chamber. This valve 11 is shown in position in Fig. 1, and its construction is shown in Fig. 2. The valve-casing is provided with a prolonged hollow stem portion 12, formed on that side of the valve-seat 13 toward the liquid-gas tank 3, and the valve 14 is attached to one end of a wire or bar 15, of any suitable metal, as silver, and which extends through the hollow stem 12 and has its other end secured to the wall of the stem 12 in any suitable way. The length of this wire or bar 15 is such as to normally hold the valve 14 off of its seat when the temperature in the expansion-chamber is just above the freezing-point. If the amount of gas escaping into the expansion-chamber is such as to reduce the temperature much below the freezing-point, the wire or bar 15 contracts by reason of the lowering of the temperature, and thereby tends to seat the valve, while a rise of temperature in the expansion-chamber tends to unseat or open the valve. The result of this action is that when more gas is passing through the valve than is necessary to lower the temperature to the desired point the valve acts to automatically decrease the amount of gas passing to the expansion-chamber, and, vice versa, when the temperature of the expansion-chamber is above the point desired the valve acts to automatically increase the flow and expansion of gas, and this lowers the temperature of the expansion-chamber. If any gas in liquid form should enter the expansion-chamber, its rapid expansion under the influence of the vacuum will lower the temperature and cause the valve 14 to automatically decrease the flow of gas, and this might be and sometimes is carried to the extent of closing said valve 14 altogether. In the conduit 4 is placed a suitable valve 16, which may be manually operated to entirely close the conduit when the apparatus is not in use.

With the apparatus thus described I proceed as follows: Within the box 2 I preferably place a liquid 17, such as strong brine, whose freezing-point is below that of water,

and in this brine I place a vessel 18, containing the water to be frozen. This vessel 18 is preferably shaped like the inverted frustum 70 of a pyramid. The valve 16 being open and the pump 6 set in motion tends to create a vacuum in the expansion-chamber. The liquefied gas from reservoir 3 reaches the expansion-chamber via conduit 4, and the rapid expansion of the gas acts to lower the temperature of the brine to or below the freezing-point of the water in the vessel 18, which is thereby frozen. The gas, which has expanded within the expansion-chamber and performed its refrigerating function, is withdrawn into the reservoir 3, to which it is conducted by the pipe 7 via the condenser or cooling-coil 8, which materially assists in liquefying the compressed gas. If in the operation of 80 the apparatus any liquefied gas enters the expansion-chamber past the valve 14, its rapid expansion under the influence of the vacuum produced by the pump 6 will cause a sudden lowering of the temperature in the expansion-chamber, thereby causing the wire or bar 15 to contract and draw the bar 14 toward its seat, and thus diminishing the opening for the passage of gas into the expansion-chamber. If the temperature of the expansion-chamber shall rise, the valve 14 will be automatically opened.

It will be seen that the apparatus is one of simple construction, operating with cheap materials and small power, and that it automatically regulates the temperature to the degree desired.

Having thus described my invention, what I claim is—

1. In an ice-making apparatus, an ice-chamber, a gas-expansion chamber surrounding the same, a reservoir containing liquefied gas, a pipe extending from the reservoir into the expansion-chamber, a valve-casing supported on said pipe within said expansion-chamber, and a thermostatic valve within said casing. 105
2. In an ice-making apparatus, a reservoir containing liquefied gas, an ice-chamber, an expansion-chamber surrounding the same, a conduit leading from the reservoir to the expansion-chamber, and a thermostat suspended in said expansion-chamber and controlling the flow of gas to said chamber. 110
3. In an ice-making apparatus, a reservoir, containing liquefied gas, an ice-chamber, an expansion-chamber surrounding the same, a conduit leading from the reservoir to the expansion-chamber, a valve-casing at the end of said conduit and within the expansion-chamber, a valve-seat within said valve-chamber, and a valve in proximity to said seat, and carried by a thermostat also in said chamber. 115

In testimony whereof I have signed this specification in the presence of two subscribing witnesses.

JOHN H. J. HAINES.
